PROCESS FOR SELECTING SINGLE COLORS
OR COLOR TONES FROM PICTURES COM-
PRISING SEVERAL COLORS OR COLOR
TONES, ESPECIALLY FOR REPRODUCTION
PURPOSES

Ladislaus Szigeti, Ujpest, Hungary

Application March 2, 1936, Serial No. 66,758
In Hungary March 1, 1935

1 Claim. (Cl. 95—5.1)

(Granted under the provisions of sec. 14, act of
March 2, 1927; 357 O. G. 5)

In the reproducing industries it is often required to select individual colors from the original multicolored drawings or pictures, which has been attained according to the processes hitherto known, for instance in three color printing, by means of color filters and by proper choice of the period of exposure respectively. However, it was not possible to select by these processes the colors only very slightly differing from each other or the individual color tones thereof, that is to say to reproduce such a color tone in such a way that it shall be alone contained in the photograph. So for example the gray or violet spots of a pattern consisting of black-gray-white and red-violet-blue colors respectively could not be selected up till now but by means of long and expensive manual work. This is disadvantageous especially in the textile industry, where the colored fabrics in general are not produced by means of three color printing, but the colors are mostly separately printed to the fabric, by which as many printing rollers and accordingly as many selections are required as the number of color tones of the pattern to be reproduced, respectively as the number of color tones of which the pattern should be made.

The selection of the colors is effected according to the invention without any manual work in a mere photographic way.

Fig. 1 of the annexed drawing shows the original pattern to be reproduced and Figs. 2 to 4 represent the individual reproductions which correspond to the steps required for selecting a color tone in accordance with the invention. Fig. 5 is a distorted cross section of the reproduction according to Fig. 2.

The original pattern to be reproduced is usually an ornamental one, however, for the sake of simplicity in Fig. 1 a pattern consisting of five strips of different color tones marked by running numbers has been shown as the original pattern. The individual color tones are represented by corresponding hatching. Now, if from the different color tones that indicated by the numeral 3 is to be selected, the pattern is photographed, that is to say the negative according to Fig. 2 is produced by means of a suitable exposure or lighting through and development with or without a color filter and eventually after interposing another layer. This negative is produced in such a way that the color tone 3 to be selected is giving a light gray image on the negative, that is the sensitive layer of the plate is altered along the strip 3' in such a manner that on the outer limiting surface of the layer a thin protecting or covering layer 6 is produced (Fig. 5), however, the

other parts of the layer or hardly changed. Namely, the sensitive layer is decomposed by the light before all at the spots where it is falling first to the said layer and by this a protecting layer is produced. Thus by properly setting the exposure it may be attained that the reproduction 3' of the color tone 3 to be selected is forming a transition between white and black, which is constituted by an unchanged or hardly changed sensitive layer and by a superposed protecting or covering layer, which usually give a pale gray color. In this case the images 1' and 2' of the color tones 1 and 2, which are darker than the color tone to be selected, will be so light that a protecting layer is not at all produced or such a layer is formed only to a negligible extent on these images, while the images 4' and 5' of the lighter color tones 4 and 5 will become so dark that the chemical transformation is produced in the whole thickness of the layer or at least in its predominant part.

Consequently, when the reproduction obtained in the above described manner by means of exposure and development, before fixing, is once more exposed in a suitable way, that is to say it is acted upon by light and this directly or after interposing a color filter or any other intermediate layer and afterwards this reproduction is again developed, the strips 1' and 2' which have evidently not lost their sensitiveness on account of the development, will become much darker and the strips 4' and 5' which have been dark already when taken, will be eventually somewhat further darkened. However, it has been found that the strip 3' keeps its original light gray color or it will be only very slightly darkened, as the protecting layer 6 being on its outer part prevents the penetration of light or it allows to pass such quantity of light only which causes a very slight darkening of the layer 3'. By this the reproduction according to Fig. 3 is obtained, in which the strip 3'' is pale and all other strips are dark respectively substantially darker than strip 3''. Now, if from this negative an advantageously hard positive is made, the reproduction according to Fig. 4 is obtained, in which only the layer 3'' resulting from the light layer 3' is dark, that is to say clearly visible, whereas the strips 1'', 2'', 4'' and 5'' resulting from the dark strips 1', 2', 4' and 5', if they are discernible at all, are so light that they do not at all disturb the reproduction. Thus, by the aid of this method a reproduction of the original picture is obtained, in which only the color spots produced with the color tone to be selected of the

original picture are contained, that is to say the desired selection has been fulfilled.

It has been mentioned that the second exposure must be a "suitable" one, and since the protecting layer 6 is not opaque, but only partially obstructs passage of light rays, it will be understood that the intensity of the second exposure must be so chosen as to be strong enough for darkening the parts 1' and 2', but not so strong that the light rays will penetrate underneath the covering layer 6. Of course, if the intensity of the second exposure is too great, that is to say the plate is exposed to light for too long a period, the light rays penetrate through layer 6 and strip 3' will be as dark as strips 1' and 2'.

It is obvious that the second exposure is to be made from the emulsion side.

From the different embodiments of the invented process I would mention that the plate or film may be in the developing liquid during the exposure or it may be dipped into the said developing liquid before exposure, by which the development is produced in the course of the exposure. Furthermore, single parts of the obtained image, in which no selection is to be effected, may be fixed after the first development; it is even possible to weakly fix the whole image or to employ another treatment such as weakening and so on, but obviously only to such extent that the parts not lighted or only slightly lighted should keep their sensitiveness. Also the second exposure may be restricted to the parts of image in which a selection is to be effected.

According to the above explanations this process is based upon the discovery that the gray tones of a developed but not fixed photographic reproduction are not considerably altered by a second properly chosen exposure and development. However, this discovery can be utilised not only in connection with the above mentioned selection, but it offers great many possibilities of use, which are mostly closely connected to selection. It is for example well known that in certain printing processes, especially in the textile industry, where owing to the dilute colors in use, furthermore, to the great absorptive capacity of the cloth to be colored the spots will become enlarged, all lines are to be made thinner and all spots smaller than they have been in the original pattern. Thus besides the selection also a reduced reproduction is to be made, in which all color spots are smaller than in the original image. This object is attained by means of the above principle in such a way that at the first exposure an out of focus image of the original pattern is made or in any other way (by means

of polarisation, etc.) provision is made that between the white and black colors a gray transition is obtained. Then this picture is once more exposed and developed in the above described way. At the second exposure only the part of the spots which is within the gray strips will become darker, that is around the individual color spots a gray limiting strip provided with a protecting layer is produced, which is not changed at the second exposure, and thus it is not contained in the final reproduction; consequently, in this reproduction the color spots produced by the second exposure are smaller by the width of said limiting strip. In this way a reduced picture is obtained. Evidently provision is to be made that the dark background being between the light (negative) color spots produced by the first exposure should be rendered pale, for instance by means of a silver solvent employed before the second exposure; should it not be so, after the second exposure the color spots would be just as dark as the background and only the limiting strip would be pale. However, after using the silver solvent, the background will have the same color as the limiting strips and the reduced spots only will be dark.

The principle of double exposure and double development is also adapted for coloring the images, as if at both exposures differently colored images are produced, a two-colored reproduction may be obtained. Moreover, the exposure may be done through any figure (design), for instance through a reticulation, by which further color effects can be attained.

I claim:

Process for manufacturing printing means for printing a color or color tone selected photographically from a picture containing several colors or color tones consisting in making from the said original picture an unfixed but developed reproduction on a light sensitive silver halide element by exposure controlled to produce a covering layer on the parts of the reproduction corresponding to the selected color or tone; exposing the said reproduction to diffused light of a value insufficient to cause alteration of the parts provided with the said covering layer but adequate to cause the other less lighted parts of the picture to be altered; developing the reproduction to obtain an image on which the said parts corresponding to the selected color or tone are more light than the other parts; fixing this picture image and making a hard positive from said image.
